UNITED STATES PATENT OFFICE.

RICHARD W. HUBBARD, OF ASHTABULA, OHIO.

HINGE.

Application filed October 16, 1924. Serial No. 744,071.

To all whom it may concern:

Be it known that I, RICHARD W. HUBBARD, a citizen of the United States, residing at Ashtabula, in the county of Ashtabula and State of Ohio, have invented new and useful Improvements in Hinges, of which the following is a specification.

My present invention pertains to hinges and it contemplates the provision of a hinge 10 that is adapted for use in connection with automobile or vehicle bodies in which it is necessary for appearance sake to employ a concealed hinge.

The invention further contemplates the provision of a hinge that is readily detachable and interchangeable and can therefore be used with equal facility on the door or the casing of the vehicle.

The invention further contemplates a concealed hinge for vehicle that is strong in construction but has the characteristics of simplicity and cheapness in manufacture, which is an important consideration as all of the elements of the hinge, can be made 25 in great quantities, as they will be exactly similar in construction when they come from the dies and machines, and hence rapid assembly is assured.

The invention in all of its details will be 30 fully understood from the following description and claims when the same are read in connection with the drawings accompanying and forming part of this specification, in which—

Figure 1 is a front elevation of my novel hinge as applied, and showing a portion of the door and casing of a vehicle body.

Figure 2 is a horizontal section taken in the plane indicated by the line 2—2 of Figure 1 and looking in the direction of the arrows.

Figure 3 is a similar view taken on the line indicated by line 3—3 of Figure 1 looking in the direction of the arrows.

Figure 4 is a sectional view illustrating my novel device with the door swung away from the frame of the vehicle.

Figure 5 is a vertical section on the line 5—5 of Figure 1 in the direction of the arrows.

Figure 6 is a similar view taken on the line 6—6 of Figure 1.

Figure 7 is a perspective view of the elements comprising my invention and 55 shown disconnected from each other.

Similar numerals of reference designate corresponding parts in all the views of the drawings.

My novel concealed hinge is illustrated as secured on a portion of a casing 1 and to a door indicated by 2 and I have designated the hinge as a whole by the numeral 3 and the door leaf is shown at 4 while the casing leaf is shown at 5, and arranged so as to secure the elements 4 and 5 I provide 60 the connector 6. The door leaf 4 is secured to the door by countersunk fasteners 7 while the leaf 5 is secured to the casing by the countersunk fasteners 8. The leaf 4 is bent as indicated at 9 to form the curved 65 member 10 and is provided on its extreme end with an ear 11 while the leaf 5 is provided with the ear 12 as clearly shown in Figure 2.

The connector 6 is provided with the ears 75 13 and 14 and I employ a pintle 15 that passes through the ears 13 of the connector 6 and the ears 12 of the leaf 5 whereby the connector and the leaf 5 are secured to each other. The pintle 16 passes through the ears 14 and ears 11 of the connector 6 and leaf 4 80 whereby said elements are secured to each other.

In the casing 1 and clearly shown in Figure 4 it will be manifest that I provide a 85 mortise 17 into which the connector 6 and its elements travel during the opening and closing of the door.

Provided over the opening on the edge of the casing where the mortise is cut, I arrange 90 a cover plate 18 that is fastened to the casing at 19 Figure 6. This cover plate 18 is bulged at 20 whereby the curved portion 10 of the door leaf 4 will be protected and guided on movement in to and out of the 95 mortise 17, and arranged in the casing leaf 5 is a longitudinal slot 21 as illustrated in Figure 7.

In the practical use of the invention, it 100 will be manifest that I may either mortise the door or the casing, and if such practice is resorted to, in respect to the door, it will simply be necessary to secure the elements in the reversed manner to that shown in Figure 4 particularly.

The device is adapted for motor vehicles and can be detachable and at the same time will not require the employment of skilled labor for adjustment.

Having described my invention, what I 110

claim and desire to protect by Letters-Patent is:—

1. In a concealed hinge, the combination of a leaf having an elongated slot therein, pintle receiving members formed on one end of the leaf; said leaf having one of its outer surfaces provided with a tongue that is formed integral with the outer surface thereof, a second leaf arranged adjacent the first leaf, a curved strap formed integral on one end of the second leaf, pintle receiving means arranged on the strap; said pintle receiving means being arranged at a point slightly below the upper and lower edges of the strap; a connector having a cut-out surface adapted to seat the pintle means of the strap and having arranged above the cut-out surface pintle receiving means that register with those of the strap and other pintle receiving means adapted to engage and register with the pintle receiving means of the first leaf; said connector being adapted to

travel into and out of the slot of the first leaf.

2. In a concealed hinge the combination of a leaf having a slot therein, pintle receiving members formed on the leaf, a tongue formed integral with the outer surface of the leaf, a second leaf, a strap formed on one end of the second leaf, pintle receiving means arranged on the strap at a point slightly below the upper and lower edges of the strap, a connector having a surface adapted to seat the pintle means of the strap and having pintle receiving means that register with those of the strap and other pintle receiving means adapted to register with the pintle receiving means of the first leaf; the connector being adapted to travel in to and out of the slot of the first leaf.

In testimony whereof I have hereunto set my hand.

RICHARD W. HUBBARD.
